(57) **CLAIM**

The ornamental design for a pet stroller, as shown and described.

DESCRIPTION

FIG. 1 is a perspective view of the pet stroller showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 1;

FIG. 10 is an enlarged view of a portion indicated with numeric 10 in FIG. 1;

FIG. 11 is an enlarged view of a portion indicated with numeric 11 in FIG. 1;

FIG. 12 is an enlarged view of a portion indicated with numeric 12 in FIG. 2;

FIG. 13 is an enlarged view of a portion indicated with numeric 13 in FIG. 2; and,

FIG. 14 is an enlarged view of a portion indicated with numeric 14 in FIG. 2.

The broken lines in the drawings illustrate portions of the pet stroller that form no part of the claimed design. The dot-dash broken lines represent the boundary of the enlarged portion and form no part of the claimed design.

1 Claim, 14 Drawing Sheets
